COOKING UTENSIL

Max S. Reiss, Wheeling, W. Va., assignor to Lisk-Savory Corporation, Buffalo, N.Y.

Filed Jan. 31, 1972, Ser. No. 222,441

Term of patent 14 years

Int. Cl. D7—02

U.S. Cl. D7—96

Fig. 1.

Fig. 2.

Fig. 3.

Fig. 4.

FIG. 1 is a side elevational view of a cooking utensil showing my new design;

FIG. 2 is a view similar to FIG. 1, but showing the cooking utensil rotated through 90°;

FIG. 3 is an exploded perspective view of the cooking utensil as viewed from the top in FIG. 1; and

FIG. 4 is an exploded perspective view of the cooking utensil as viewed from the bottom in FIG. 2.

I claim:

The ornamental design for a cooking utensil, as shown and described.
